UNITED STATES PATENT OFFICE.

FRANZ HUTTER, OF NEW YORK, N. Y., ASSIGNOR TO THE McCALL COMPANY, A CORPORATION OF NEW YORK.

MANUFACTURE OF GARMENT PATTERNS.

No Drawing.

Application filed April 20, 1920. Serial No. 375,247.

To all whom it may concern:

Be it known that I, FRANZ HUTTER, formerly a subject of the Emperor of Austria-Hungary, having declared my intention of becoming a citizen of the United States, and a resident of the city, county, and State of New York, have invented certain new and useful Improvements in the Manufacture of Garment Patterns, of which the following is 10 a specification.

In my Patent No. 1,887,723, I have described a garment pattern comprising a number of pieces having printed thereon in determined locations, directions or graphic 15 indications for the cutting or the use of the corresponding piece of the fabric from which the garment is to be made, as a substitute for the old and well known paper patterns in which various lines and points 20 were marked by special sorts of perforations, and a separate table or chart was used to tell what each kind of perforations meant. The patterns have to be sold cheaply and transported to great distances and, therefore, 25 have had to be made on very light paper, as a great many sheets of such paper can be perforated in one operation. Attempts have been made from time to time to provide the pieces of the pattern with one or more 30 printed signs. But such signs have generally been put on by hand, as by means of a rubber stamp or the like, so as to be quite expensive and not capable of exact location on the pattern-piece; as would be necessary 35 for example to mark the line of a hem or a point to be matched with a corresponding point on another piece. It has also been proposed to print lines and legends of various sorts on linen, muslin and other materials, but none of such suggestions have 40 come into commercial use, chiefly because they did not, in my judgment provide the accuracy required and also the possibility of manufacture cheaply in quantities.

According to my present invention I provide a method by which the patterns can be produced in vast quantities economically and in light and small packages so that the cost of shipment over a wide territory is not too great. The product of my process is a pattern which can be used easily and without loss of time by inexperienced persons, is even more accurate than those made by the old method; and this product is obtained by a 50 process of manufacture involving certain economies impossible under the old method. Various other advantages are referred to in detail hereinafter.

The improved pattern comprises a number of separate pieces of suitable shape and of paper which can be thicker than the ordinary tissue paper from which patterns have been made. Directly on each piece of the pattern I print graphic indications which are in exactly determined locations and 60 which indicate to the user the manner of cutting and use of the corresponding pieces of the fabric which are to be combined in the garment. These indications may be signs such as lines, triangles and so forth or they 65 may be words, and generally they will consist of both signs and words so as to leave no doubt of the exact location of a line or point on the fabric and of the use which is to be made of this line or point.

In the production of the patterns I take a 70 large sheet from which the pieces are to be cut. In some cases the sheet may contain all the pieces of a complete pattern. In other cases, especially where a considerable number of large pieces is involved, the sheet in question may contain less than all the pieces 75 of the pattern. Or one sheet may contain a plurality of complete patterns or a whole pattern and parts of another or parts of one 80 pattern and parts of another. In fact, the grouping of the patterns on the printed sheets will be varied considerably by manufacturing and commercial questions in connection with the several patterns. On this 85 sheet I print in accurately determined locations for each of the intended pattern pieces the graphic indications desired. Preferably at the same time I print the outline of each piece as a guide to the subsequent cutting, although I may depend on the cutting 90 machine to follow the correct outline without the previous printing of it on the sheets or with the printing of it on only the top sheet of a stack of sheets which are to be cut 95 at one operation. The printing operation at 100 described is repeated on a number of sheets, printing the graphic indications referred to in the same locations on the successive sheets. The printing can be done most rapidly on a 105 roll of paper consisting in effect of a number of separate sheets which, however, are only cut from the roll after printing.

The sheets thus printed are stacked in exact register with each other and a cutting 110

2
machine or hand-cutting knife, which may be of the same type as that now used for cutting stacks of tissue paper patterns, is employed to cut out the separate pieces of the 5 pattern from all the sheets of a stack simultaneously. Accuracy of register may be insured by stacking the sheets on pins which are made to pass through points marked in identical locations on the successive sheets; 10 but this will not generally be necessary. This cutting out operation completes the manufacture of the patterns in the simplest embodiment of the invention and it is only necessary to gather the various pieces of 15 each pattern together in the usual way.

The different pieces of the pattern should be arranged on the finished printed sheet preferably in such a way as to economize space, with projecting portions of one entering re-entrant portions of another. They 20 may, however, be arranged in such a way that the grain of the goods runs in the same direction on all pieces. Whatever their relative arrangement the outlines of the different 25 pieces must be separated from each other sufficiently to allow a margin of inaccuracy in the subsequent printing of the pieces and the cutting of them out from the sheet. In practice I find that the outlines of the pieces 30 should be spaced apart never less than one-half an inch. To secure this arrangement the different pieces of the cardboard model are cut out and placed in the determined arrangement upon a transparent and preferably varnished sheet of paper, and are used 35 as models by which the outlines of the pieces are drawn on the transparent paper with a pen in opaque ink. The lines and notches on the several pieces of the cardboard model 40 are then drawn in opaque ink within the outlines of the several pieces on the transparent sheet; and the names, numbers and legends required are also marked on the several pieces on the transparent sheet by means 45 of rubber stamps or other devices with opaque ink, the lines being first protected from injury by a gelatine coating if necessary.

A very useful feature of the complete pattern is the tinting of each pattern piece so 50 that it stands out separately on the sheet. This result I secure with an accuracy and economy not otherwise obtainable, by the following method. When the transparent 55 sheet has been carried to the point described above I cut the several pieces of the pattern out of another sheet of transparent paper which is uniformly tinted, preferably by stippling or fine dots arranged closely and 60 approximately uniformly over the entire surface, since this form of "tinting" is most easily and accurately re-produced in printing. These tinted pieces are then pasted over the outlines of the corresponding pattern-pieces which have been drawn on the 65

transparent paper. In fact, it is not necessary to have drawn the entire outline, the edge being possibly indicated by the tinted piece and being very distinct from the edge drawn by a solid line.

The transparent sheet having the pattern piece thus lined, lettered and tinted and in proper relative arrangement may be called the "transfer", and is the final model from 70 which the printing plate is made.

The printing plates may be used in an offset web press with a delivery designed to produce an accurate stacking of the printed paper sheets on top of each other. A large 80 number, say 1,000, of the printed sheets are stacked and pattern-pieces are cut out from all the sheets in the stack at once preferably by means of a band saw. In this operation the reason will be clear for the leaving of a space of one-half an inch or more between 85 the edges of the different pattern-pieces as printed on the sheet. The band saw is arranged to cut the pieces with a margin of about one-quarter of an inch outside of the printed outline of each piece. This will allow the operator to work very rapidly, and consequent variations in the cutting edge will be of no importance, the finished pattern-piece having its true outline printed thereon and having an unprinted margin of 90 about one-quarter of an inch all around but capable of considerable inaccuracy without affecting the value of the pattern. The band saw may be guided by an attachment ending in a point standing exactly a quarter of an 100 inch away from the knife and with which the operator will follow the printed outline of the pattern-piece.

The tint extending over the exact area of the pattern-piece holds the piece together 105 in the eye of the observer, and aids the operator in cutting out the pattern pieces by presenting a striking difference between the pattern pieces and the spaces between them, through which the cutter must pass and the 110 quarter inch margin left over in cutting becomes a negligible element so that the irregularities due to the sheets not being stacked in exact position on top of one another will be harmless. Previous proposals 115 to print more or less of the outline of pattern-pieces have been regarded as futile because of the impossibility, in commercial manufacture, of cutting accurately and simultaneously a large number of printed patterns. These features of providing a margin and then eliminating all uncertainty resulting from the margin by holding the piece together to the eye by means of a tint, 120 are, therefore, of considerable importance 125 in the commercial practice of the invention.

In use, certain pattern-pieces are placed with one edge coinciding with a fold, but not with a cutting edge of the fabric. I 130 prefer to distinguish such edges by making

the outline of the pattern-pieces in solid black lines except such an edge as is to be placed on a fold, leaving only the edge of the tint along this line. Therefore, in the course of manufacture such pattern-pieces will be marked on the transparent transfer with a line extending all around except on the fold edge, and the stippling or tint will overlie the whole area as usual; and this effect will be repeated in the printing plate and in the printed pattern sheet.

In fact, though I have described with great particularity of detail certain specific processes and steps embodying my invention, yet it is not to be understood therefore that the invention is restricted to the particular details disclosed. Various modifications thereof in detail and in the steps of the process and order may be made by those skilled in the art without departing from the invention. For example, the transfer sheet is not necessarily transparent. It may be opaque and still be reproduced on the printing plate by known photographic printing methods.

What I claim is—

1. The method of manufacturing a num-

ber of identical patterns for a garment which includes the following steps,—printing on each of a number of sheets in succession pattern pieces separately outlined and spaced apart from one another, stacking said sheets upon one another and cutting the separate pattern pieces from the stack by passing the cutter through the spaces between the separate pieces so as to leave each piece with a margin around its outline and with inaccuracies in register affecting the margins only.

2. The method of manufacturing a number of identical patterns for a garment which includes the following steps,—printing on each of a number of sheets in succession pattern pieces each in a flat tint and spaced apart from one another, stacking said sheets upon one another and cutting the separate pattern pieces from the stack by passing the cutter through the spaces between the separate pieces so as to leave each piece with a margin around it.

In witness whereof, I have hereunto signed my name.

FRANZ HUTTER.
